GRANULAR MATERIAL PACKAGE AND
METHOD OF PRODUCING THE SAMEPaul Francis Collins, Columbus, Ohio, assignor to
The Columbus Dental Manufacturing Com-
pany, Columbus, Ohio, a corporation

Application January 6, 1936, Serial No. 57,829

10 Claims. (Cl. 206—63.5)

My invention relates to a package of granular material and method of making the same. It has to do particularly with a package of dental investment compound and method of producing it, though it is not necessarily limited thereto, since the principles of my invention as regards both package and method may be applicable to other granular materials.

Dental investment compounds are made of varying constituents. Under present day practice, they usually embody siliceous refractory material, such as silica, cristobalite and the like, and a calcium sulphate binder, such as plaster of Paris or the like. In addition to these ingredients, other materials, such as boric acid, graphite, asbestos, fiber, pumice stone, coloring matter, et cetera, have been used singly or in combination, though ordinarily in substantially smaller proportion than the above chief ingredients. One investment compound which I have invented and which is now on the market also embodies a copper powder.

These materials are commonly mixed together in powdered form and in such a way that the mixture is uniform throughout. This is important because of the fact that these dental investment compounds are sold to the trade in packages ranging from 1 pound to 100 pounds and relatively small portions thereof are, from time to time, withdrawn from the package by the dentist or dental technician for the making of casting molds or for use in soldering operations. Each portion so withdrawn should possess its proper percentage of each ingredient initially used in mixing the compound. The necessity for this is illustrated by the fact that the dental investment compounds are sold to the dentist or laboratory technician with definite assurance, frequently printed upon the container, that they will possess given qualities, such as definite setting expansion, definite thermal expansion, definite setting time and definite crushing strength.

The importance of this is illustrated by the fact that under present day methods of precision casting of precious metal inlays, of precious metal against embedded metals and of other precious metal units, it is the practice to construct a casting mold of these dental investment compounds and to rely upon the combined setting and thermal expansion of the mold as a factor which will compensate for the shrinkage of the precious metal casting upon cooling. In other words, the mold, upon subjection to the heating operations necessary as a preliminary to the casting operation, will have a cavity definitely larger than the

cooled cast product so that the cast metal when molten will be larger to the exact extent necessary to insure that, after shrinkage upon cooling, the casting will be of exactly the right size. Also, each mold should contain a predetermined percentage of small grain particles to insure proper fineness of detail and a predetermined percentage of relatively large grain particles to insure adequate porosity and strength. Also, as indicated above, the setting time and crushing strength must be definite and adequate in each mold and this is, of course, dependent upon the proper mixture of the ingredients in each portion withdrawn by the dentist or laboratory technician for use.

In the prior art, considerable effort has been devoted to the proper mixing of the ingredients so that the relative percentages thereof will be uniform throughout upon the completion of the mixing operation. Prior to my invention, however, it has been customary to place the desired weight of the mixed compound in the container in which it is to be marketed in a loose state. Owing to the difference in nature of these different ingredients, they differ in grain size, in grain shape and in specific gravity and, in the main, these differences are unavoidable. Thus, when the compound is placed in its container in its loose state, the ensuing handling and shipment inevitably results in such a stratification or migration of the different materials that, by the time the dentist or laboratory technician is ready to withdraw successive portions from the container, the compound is not in its originally mixed state, i. e., not uniformly mixed throughout the container. The result is that the successive portions of compounds withdrawn from the container will not have uniform percentages of the proper ingredients uniformly distributed throughout. Thus, one portion may have an excess of siliceous material and another portion may have an excess of calcium sulphate material and some portions will have more metal powder than others, while the other ingredients that may be in the compound will not be present in successive portions in the proper proportions. The dentist or laboratory technician, therefore, could not reliably depend upon obtaining any accuracy of result in carrying out his technical operations and failures in obtaining proper results are for the reasons stated very commonly caused.

In the prior art, manufacturers have resorted to the crude practice of marking on the containers such instructions as "Shake before using" or "Stir before using". However, the mixing of the ingredients in a proper manner is a type of

operation requiring the use of mechanical apparatus, and the steps normally taken by the dentist or laboratory technician in pursuance of these instructions are insufficient and inadequate to restore the compound to its initial properly mixed state.

My invention has to do with the provision of a package of dental investment compound which will remedy these drawbacks of the prior art. It has for its object the provision of such a package that the dental investment compound which has been properly mixed to provide the various factors, such as proper setting expansion, proper thermal expansion, proper relative percentages of grain sizes, proper porosity, setting time and crushing strength will be retained in such properly mixed condition until it reaches the dentist or laboratory technician and has been opened by him preliminary to its use in the production of molds or in soldering operations.

This application is a continuation as to broad method features, and a continuation in part with regard to the package produced thereby, of my application, Serial No. 715,977, filed March 16, 1934, for Method of packing homogeneous mixtures of pulverized heterogeneous materials, which application was allowed on October 10, 1935 and discloses one method of producing a packaged article of the character constituting the present invention.

In its preferred form, my invention comprises a package of dental investment compound wherein the compound has been introduced into its container in a properly mixed state and has been subjected to the application of pressure tending to maintain it against the action of disturbing forces when the container is sealed so that all or substantially all danger of stratification and settling out of ingredients of the compound under the normal conditions of handling and shipping is removed. It further contemplates the closing of the container in such a way that the compressed compound is subjected either directly or indirectly to pressure from the container walls and closure of a kind and degree to maintain the compound in its compressed state. It still further contemplates a novel method of producing the package.

A preferred embodiment of my invention is illustrated in the accompanying drawings wherein similar characters of reference designate corresponding parts and wherein:

Fig. 1 is a perspective view, partly broken away, of a package of my dental investment compound, in which package, the container takes the form of a friction top can.

Fig. 2 is a side elevation, partly broken away, of the package shown in Fig. 1.

Fig. 3 is a diagrammatic illustration of the essential parts which I preferably utilize in effecting an initial compaction of a dental investment compound in a container.

Fig. 4 is a view similar to Fig. 3, showing the initially compacted state of the compound after the compressing plunger has compacted it and been removed.

Fig. 5 is a diagrammatic illustration of a second step which I preferably use, in the type of container shown, for finally compacting the material in the container.

Fig. 6 is a vertical section of the same container with a compound finally compacted therein and with the funnel removed, the container being left in the clamping unit.

Fig. 7 is a perspective view, partly broken away,

of the clamping unit shown in the preceding figure.

Fig. 8 is a vertical section of a completed package resulting from the packaging steps of Figs. 3 to 5 inclusive, together with certain additional steps which complete the package.

Fig. 9 is a diagrammatic illustration of a type of apparatus which I preferably use in packaging compounds in larger containers, such as 100 pound drums.

Fig. 10 is a vertical section of a package produced in accordance with the method illustrated in Fig. 9.

In the drawings and referring particularly to Figs. 1 to 8, inclusive, there is shown a container 1 which is generally known as a friction top container. This container is substantially cubical and has a top wall 2 which is provided with a circular opening 3. A closure for this circular opening is shown at 4 and, as will be well understood, this closure is designed to fit tightly within each opening and be held firmly therein by frictional contact.

The compound is designated A and, mounted in a depression in the top of the compound 25 is a cylindrical box B containing a roll of asbestos paper which is commonly furnished the customer with each package of the compound, for his use in certain operations in forming the molds from the compound. Literature containing instructions for the use of the compound and various data may also be placed in the box as illustrated at C.

In the preferred method of producing my package with a container of the type indicated, the 35 container with its top removed is preferably mounted in a clamping unit comprising a base 5 with a raised portion 6 substantially identical in area with the base of the container. Co-operating with this base is a clamping unit embodying L-shaped members 7 and 8 which I hinge together as at 9. These L-shaped members are preferably provided at those edges opposite their hinged edges with handles 10 and 11 which assume parallel relation when the clamping unit is 45 closed. The handle 10 preferably has, pivotally mounted thereon, a hook-like member 12 which hooks over the handle member 11 for holding the clamping unit closed. The top edges of the clamping members 7 and 8 are provided with 50 inwardly extending L-shaped lugs 13 with horizontal legs whose lower surfaces are at a slightly higher level than the top edges of the clamping members.

Designed for cooperation with this clamping 55 unit is a funnel 14, shown in Figs. 3 and 4. Likewise designed for cooperation therewith are plungers 15 and 16 which are shown respectively in Figs. 3 and 5 and which may be actuated by a suitable type of actuating means.

In producing my package with the type of container described, the container is mounted within the clamping unit, as illustrated in Fig. 3. Likewise, the funnel 14 is mounted within the clamping unit so that its base flange 18 rests upon the top wall 2 of the container 1 while the cylindrical portion of the funnel registers with the circular opening 3 of the top wall of the container and is in concentric relation therewith.

The properly mixed compound is then introduced into the container through the funnel in such volume that a portion of it will extend substantially to the top of the cylindrical wall of the funnel. Then, the plunger 16 is forced down- 70 75

wardly under such pressure that the compound is initially compacted both immediately below the plunger and spread laterally to the sides thereof and firmly forced upwardly against the under 5 surface of the upper wall 2 of the container. The plunger 16 is then withdrawn and leaves a rounded concavity in the upper surface of the compound, as illustrated in Fig. 4. More of the properly mixed compound is then introduced 10 through the funnel 14 into the container. Then, the plunger 17 is forced downwardly through the funnel to compact this newly added compound. This plunger 17 compacts the compound to a 15 final degree and produces a cylindrical depression as shown at D in Fig. 6, for the reception of the box containing the asbestos paper. It also produces a depression E of somewhat larger diameter than the depression D for the reception of the literature and the superimposed friction 20 top 4.

The package is completed by placing the box B in position, superimposing the literature thereon and then forcing the friction top 4 into firm contact with the literature. The pressure applied 25 by the friction top is transmitted through the literature and the box to the body of the compound and also, to some extent, to that portion of the compound which surrounds the lower portion of the friction top. Owing to the pressure 30 applied by the plunger before the top is applied and owing to the pressure applied by the top itself after it is in position, there is produced a package of dental investment compound or other similar material which will reach the consumer in a properly mixed state, notwithstanding 35 the various forces to which it is subjected in handling or shipping.

In the somewhat modified form of package, illustrated in Figs. 9 and 10, the roll of asbestos 40 paper and the container therefor are normally omitted. Furthermore, I preferably use only one application of pressure for compacting the material in the container. The containers which are filled in this way are preferably those designed 45 for shipment of the compound in 25 pound and 100 pound lots.

The preferred method of producing such packages is illustrated in Fig. 9. It involves the use 50 of a cylindrical funnel or tube 20 which is of substantially identical diameter with the container 21. This funnel or tube 20 may be held in concentric registering relation with the container 21 by depending fingers 22 of the tube 20. It will be noted that the container has straight side 55 walls.

The plunger which I preferably use is of frusto-conical form and its base is of substantially the same diameter as the interior diameter of the container 21. This plunger is provided with a 60 series of ducts 23 extending from the base thereof to the atmosphere. The lower ends of these ducts with one-way flap valves 24, so that the compound will not enter the ducts, though the air may pass into the space between the base of the plunger and the compound, as this plunger is 65 lifted from the compound after completion of its compressive action, thus preventing formation of a partial vacuum and consequent lifting of upper layers of the compound.

70 After the plunger has been forced downwardly under sufficient pressure to adequately compress the compound within the container, it is withdrawn and the funnel or tube 20 is removed, preferably, literature is placed upon the top of the 75 compressed compound and the closure 25 is fas-

tened upon the container in such a way that it applies pressure to the literature and consequently to the compound beneath.

It will be seen that I have provided a package of dental investment compound which, providing the compound has been placed in the container in a properly mixed state, will insure that this compound will reach the consumer in its properly mixed state. The pressure applied by the plungers is sufficient to prevent any material 10 settling thereafter and the pressure applied by the closure is sufficient to maintain the compound against any material stratification or migration of the grains of the material under disturbing forces. The result is that, when the 15 dentist or laboratory technician opens the container preparatory to use of the compound, any portion that he may select therefrom will contain the proper constituents uniformly distributed therethrough in proper percentages to insure 20 that he will obtain proper setting expansion, proper thermal expansion, proper setting time, and proper crushing strength, as well as proper relative percentages of different grain sizes to insure fineness of detail and proper strength and 25 porosity of the mold, if the compound is to be used for casting molds.

It will be understood that this type of package is not limited to dental investment compounds. It will be applicable to other compositions of 30 granular material which may differ in grain size, grain shape or specific gravity, wherever it is desirable to maintain the various ingredients properly distributed throughout the mass during handling or shipping. It is also to be understood 35 that the invention is not limited to the particular method or steps of the method herein described for producing the package, as conceivably other ways of producing the same may be employed within the spirit and scope of the appended 40 claims.

Having thus described my invention, what I claim is:

1. A package of material comprising a sealed container and filler therein consisting of a granular compound of different materials which differ in grain size, shape or specific gravity stored therein in a definitely mixed state to insure uniform conditions of distribution of various batches that may be removed for use from said container 50 under various conditions to which such material is to be subjected in the use thereof, said material being packed in the container under such pressure as will substantially prevent alteration of its initial state of mixture under disturbing 55 forces and with the walls of said container exerting sufficient pressure against all sides of the material to maintain it against the action of such forces substantially in its initial packed state.

2. A dental investment material package comprising a container, a filler of investment material in said container in the form of a granular compound of different materials which differ in grain size, shape and specific gravity and which are stored therein in a definitely mixed state to insure specific and uniform reactions of various batches that may be removed from said container under the various conditions to which such compounds are subjected in the use thereof, said mixture being packed with the container under such pressure as will maintain it against alteration of its initial state of mixture under disturbing forces, and a closure for said container bearing on the material and coating with the walls of the container to exert sufficient pressure upon said 70

packed material to maintain it substantially in its initial packed state against the action of such forces.

3. A dental investment material package comprising a container provided in its upper wall with an opening to receive a friction top, a filler of investment material packed in said container in the form of a granular compound of different materials which differ in grain size, shape and specific gravity and which are packed therein in a definitely mixed state to insure specific and uniform reactions of various batches that may be removed from said container under the various conditions to which such compounds are subjected in the use thereof, said mixture being packed under such pressure within and against the walls of the container as will maintain it against alteration of its initial state of mixture against disturbing forces, and a friction top sealing said opening and having a portion projecting into the container and cooperating with the walls of the container to exert sufficient pressure against all sides of the material to maintain it in its initial packed state.

23. 4. A dental investment material package comprising a container, a filler of investment material contained therein in the form of a granular compound of different materials which differ in grain size, shape and specific gravity and which are packed therein in a definitely mixed state to insure specific and uniform reaction of all parts of the material in said container under the various conditions to which such compositions are subjected in the use thereof, said mixture being packed under such pressure as will maintain it against migration of its components from their initial state of mixture, and said container having sealing means cooperating with its walls in the sealed condition of the container to exert sufficient pressure upon such packed material to maintain it against the action of disturbing forces substantially in its initial packed state.

45. 5. A granular material package comprising a container provided in one of its walls with a filling and discharge opening, a filler packed in said container in the form of a granular compound of different materials which differ in grain size, shape and specific gravity and which are packed therein in a definitely mixed state to ensure specific and uniform reactions of various batches that may be removed from said container under the various conditions to which such compounds are subjected in the use thereof, said mixture being packed under such pressure within and against the walls of the container as will maintain it against alteration of its initial state of mixture against disturbing forces, and a closure for said opening in the container having a portion projecting into the container and bearing on the material and cooperating with the walls of the container to exert sufficient pressure against all sides of the material to maintain it in its initially packed state.

65. 6. The method of filling containers with pulv-
erulent or granular homogeneous mixtures of heterogeneous materials of different specific gravities for the purpose of maintaining the homogeneity of the mixture in a predetermined mixed state for a specified use and preventing separation of the components thereof from such state according to their different specific gravities through forces exerted during the handling or shipment of the package, which consists in compounding a mixture having predetermined physical properties for a specified use and packing

the material in a container in the predetermined mixed state under pressure of a degree to render the components of the material self-supporting against stratification shifting from the predetermined mixed state under disturbing forces. 5

7. The method of packing in containers dental investment compounds in the form of granular aggregates of different materials which differ in grain size, shape or specific gravity and which are so mixed as to insure specific and uniform reactions of all parts of the compound in said container under the various conditions to which such compositions are subjected in the use thereof and whereby stratification separation of the components of the packed mixture under disturbing forces is prevented, which comprises compounding a mixture having predetermined physical properties for a specified use, introducing the compound into the container in the properly mixed state, applying sufficient pressure to the mixture 20 in the container to compact it to a degree that will substantially prevent migration of the grains and stratification separation of the components of the compound from their initial properly mixed state under disturbing forces, and then sealing 25 the container so as to maintain the packed material in such compacted state.

8. The method of packing in containers dental investment compounds in the form of granular aggregates of different materials which differ in grain size, shape or specific gravity and which are so mixed as to insure specific and uniform reactions of all parts of the compound in said container under the various conditions to which such compositions are subjected in the use thereof, and whereby stratification separation of the components of the packed mixture under disturbing forces is prevented, which comprises compounding a mixture having predetermined physical properties for a specified use, introducing the compound into the container in the properly mixed state, applying sufficient pressure to the mixture in the container to compact it to a degree that will substantially prevent migration of the grains and stratification separation of the components of the compound from their initial properly mixed state under disturbing forces, and then applying a closure to such container so that it exerts sufficient pressure upon such packed materials to maintain it substantially in its initial 50 compacted state. 45

9. The method of filling containers with pulv-
erulent or granular compounded mixtures of materials of a precise composition for designed technical action and which tend to separate under disturbing forces, for the purpose of maintaining the mixture in a predetermined mixed state for a specified use and preventing separation of the components thereof from such state through forces exerted during the handling or shipment of the package, which consists in packing the material in a container in the predetermined mixed state under pressure of a degree to hold it uniformly mixed, each portion having an analysis substantially in accordance with its originally compounded state, and then sealing the container by closure means exerting pressure on the material to maintain the mixture in such predetermined mixed state. 60

10. The method of packing in containers dental investment compounds and other like blended homogeneous mixtures of solid dry heterogeneous materials of different specific gravities and/or different grain sizes, normally tending in a certain state of freeness to separate under agitation into 70 75

their classification strata, so as to maintain the homogeneity of the mixture during handling or shipment movements of the packed container tending to cause such agitation and separation of the components of the mixture, which consists in compounding the mixture in a predetermined blended homogeneous state packing the mixture in the container in such state until the container is tightly filled under an applied packing pres-

sure proportioned with regard to characteristics of the mixture to a degree to cause each grain thereof to be supported against separating forces with a generally equalized pressure from other surrounding grains from top to bottom of the mixture, and then sealing the container to maintain the equalized support of the grains.

PAUL FRANCIS COLLINS.
